UNITED STATES PATENT OFFICE.

EMIL NYBACK AND EMIL NYMAN, OF HOQUIAM, WASHINGTON.

BERTH MOUNTING.

Application filed April 2, 1925. Serial No. 20,253.

To all whom it may concern:

Be it known that we, EMIL NYBACK and EMIL NYMAN, citizens of Finland, residing at Hoquiam, in the county of Grays Harbor and State of Washington, have invented certain new and useful Improvements in Berth Mountings, of which the following is a specification, reference being had to the accompanying drawings.

10 This invention relates to mountings for ships' beds or berths and more particularly to a mounting so constructed as to eliminate strain of the bed and to maintain the bed at all times in horizontal position.

15 A further and more specific object of the invention is the improvement of gimbal joint structure employed for supporting the bed enabling the production thereof at a moderate rate while at the same time increasing 20 the rigidity of the structure.

These and other objects we attain by the construction shown in the accompanying drawings, wherein for the purpose of illustration is shown a preferred embodiment of 25 our invention and wherein:—

Figure 1 is a perspective view of a berth supported in accordance with our invention;

Figure 2 is a vertical sectional view through the gimbal joint;

30 Figure 3 is a perspective of the cross bars of the gimbal joint; and

Figure 4 is a detailed sectional view showing the mounting of the supports for the bed upon the gimbal joint.

35 Referring now more particularly to the drawings, the numeral 10 indicates a ceiling attached support in the form of an inverted U, the central portion of which is rigidly secured to a hanger 11 which is in turn rigidly secured to the ceiling 12, as at 13.

The ends of the arms of the U-shaped support engage with pivots 14 formed by directing through a gimbal ring 15 a bar 16 which is circular in cross section and of sufficient 45 length to project beyond the side faces of the ring. This bar has its under surface notched, as at 17, for the passage of an oppositely notched similar bar 18, the ends of which likewise project beyond the ring 15 and are formed with pivots 19 for the reception 50 of supports 20 for a bed 21. It will be obvious that the universal movement provided by the gimbal ring and its connection to the supports 10 and 20 will permit the bed 55 at all times to remain in horizontal position regardless of the angle which is assumed by

the vessel in which the berth is arranged. Particular attention is directed to the construction of this gimbal ring. The bars 16 and 18 connected to the upper and lower 60 supports respectively are notched upon their under and upper faces respectively to permit their passage and at the same time permit use of a straight bar.

It will be obvious that strain of weight 65 supported from the ring upon the ends 19 of the bar 18 will tend to flex the center of this bar upwardly and with the weight of the ring itself and of this load which is applied to the outer ends or pivots 14 of the 70 bar 16 will tend to flex the center of the bar 16 downwardly. These bars will, therefore, tend to flex in opposite directions with substantially equal forces, offsetting the stress 75 which is placed thereon and thereby permitting the use of lighter bars 16, 18, that could otherwise be employed. Furthermore, the interengagement of these bars at the notches thereof will effectually prevent longitudinal shifting of either of the bars and the pivots 80 14 and 19 will, therefore, always be properly projected for engagement with their respective supports.

Since the structure hereinbefore set forth is capable of a considerable range of change 85 and modification without materially departing from the spirit of our invention, we do not limit ourselves to such specific structure except as hereinafter claimed.

We claim:—

1. In a support for ships' berths, a support adapted to be engaged with a ceiling and embodying spaced arms, a second support having spaced arms secured to the berth and projecting upwardly therefrom, and a 95 gimbal ring structure for connecting said supports comprising a ring, bars extending at right angles and diametrically of said ring and having notched engagement one with the other, the ends of said bars projecting to provide pivots for engagement with the respective supports.

2. In a support for ships' berths, a support adapted to be engaged with a ceiling and embodying spaced arms, a second support having spaced arms secured to the berth and projecting upwardly therefrom, and a gimbal ring structure for connecting said supports comprising a ring, bars extending at right angles and diametrically of said 100 ring and having notched engagement one with the other, the ends of said bars projecting to provide pivots for engagement with the respective supports.

jecting to provide pivots for engagement with the respective supports, the bar the ends of which is engaged with the ceiling attached support being notched upon its under surface, the bar engaged with the berth support being notched upon its upper surface whereby strains applied to either of said bars tend to flex the bar from the other of the bars.

10 3. In a support for ships' berths, a support adapted to be engaged with a ceiling and embodying spaced arms, a second support having spaced arms secured to the berth

and projecting upwardly therefrom, and a gimbal ring structure for connecting said supports comprising a ring, crossed diametrically extending bars carried by said ring and with which the ends of said arms are engaged, said bars having engagement one with the other whereby each opposes flexure 20 of the other upon the application of weight to said supports through the ring.

In testimony whereof we hereunto affix our signatures.

EMIL NYBACK.
EMIL NYMAN.
